(57) **CLAIM**

I claim, the ornamental design for a cable clip, as shown and described.

DESCRIPTION

FIG. 1 is a perspective front view of a cable clip, showing my new design;

FIG. 2 is a front view thereof;
FIG. 3 is a rear view thereof;
FIG. 4 is an enlarged left side view thereof;
FIG. 5 is an enlarged right side view thereof;
FIG. 6 is a top view thereof;
FIG. 7 is a perspective rear view thereof;
FIG. 8 is a bottom view thereof;
FIG. 9 is a perspective front view of my new design, in another embodiment;
FIG. 10 is a front view thereof;
FIG. 11 is a rear view thereof;
FIG. 12 is an enlarged left side view thereof;
FIG. 13 is an enlarged right side view thereof;
FIG. 14 is a top view thereof;
FIG. 15 is a perspective rear view thereof;
FIG. 16 is a bottom view thereof;
FIG. 17 is a perspective front view of my new design, in another embodiment;
FIG. 18 is a front view thereof;
FIG. 19 is a rear view thereof;
FIG. 20 is an enlarged left side view thereof;
FIG. 21 is an enlarged right side view thereof;
FIG. 22 is a top view thereof;
FIG. 23 is a perspective rear view thereof;
FIG. 24 is a bottom view thereof;
FIG. 25 is a perspective front view of my new design, in another embodiment;
FIG. 26 is a front view thereof;
FIG. 27 is a rear view thereof;
FIG. 28 is an enlarged left side view thereof;
FIG. 29 is an enlarged right side view thereof;
FIG. 30 is a top view thereof;
FIG. 31 is a perspective rear view thereof;
FIG. 32 is a bottom view thereof;
FIG. 33 is a perspective front view of my new design, in another embodiment;
FIG. 34 is a front view thereof;
FIG. 35 is a rear view thereof;
FIG. 36 is an enlarged left side view thereof;
FIG. 37 is an enlarged right side view thereof;
FIG. 38 is a top view thereof;
FIG. 39 is a perspective rear view thereof;
FIG. 40 is a bottom view thereof;

(Continued)

FIG. 41 is a perspective front view of my new design, in another embodiment;
 FIG. 42 is a front view thereof;
 FIG. 43 is a rear view thereof;
 FIG. 44 is an enlarged left side view thereof;
 FIG. 45 is an enlarged right side view thereof;
 FIG. 46 is a top view thereof;
 FIG. 47 is a perspective rear view thereof;
 FIG. 48 is a bottom view thereof;
 FIG. 49 is a perspective front view of my new design, in another embodiment;
 FIG. 50 is a front view thereof;
 FIG. 51 is a rear view thereof;
 FIG. 52 is an enlarged left side view thereof;
 FIG. 53 is an enlarged right side view thereof;
 FIG. 54 is a top view thereof;
 FIG. 55 is a perspective rear view thereof; and,
 FIG. 56 is a bottom view thereof.
